CLAIM

We claim the ornamental design for an X-ray apparatus, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of an X-ray apparatus according to an embodiment.

FIG. 2 is a rear view of the X-ray apparatus according to the embodiment.

FIG. 3 is a top view of the X-ray apparatus according to the embodiment.

FIG. 4 is bottom view of the X-ray apparatus according to the embodiment.

FIG. 5 is a view from the right side of the X-ray apparatus according to the embodiment.

FIG. 6 is a view from the left side of the X-ray apparatus according to the embodiment; and,

FIG. 7 is a perspective view of the X-ray apparatus according to the embodiment.
